[57] CLAIM

The ornamental design for a paneled mirror, as shown and described.

DESCRIPTION

FIG. 1 is a front view of a paneled mirror showing my new design.

FIG. 2 is a rear view of the mirror shown in FIG. 1.

FIG. 3 is a top view of the mirror shown in FIG. 1.

FIG. 4 is a bottom view of the mirror shown in FIG. 1.

FIG. 5 is a right side view of the mirror shown in FIG. 1. FIG. 6 is a left side view of the mirror shown in FIG. 1; and, FIG. 7 is a top and left side perspective view of the mirror shown in FIG. 1.

The broken lines are for environmental purposes only and form no part of the claimed design.
